UNITED STATES PATENT OFFICE

2,010,193

BUNCH BUILDER

Jesse Lee Lyle, Danville, Va.

Application June 13, 1934, Serial No. 730,490

5 Claims. (Cl. 242—43.7)

This invention relates to a mechanism designed for use in building the bunch on filling the quills employed as part of spinning machine construction, and aims to improve generally the construction of the bunch builder bobbin forming attachment for spinning machines, shown and described in my Patent No. 1,797,353, issued March 24, 1931.

An important object of the invention is the provision of means for insuring the positive operation of the ring rail of the spinning frame, whereby the bunch will be properly and accurately formed, with a minimum amount of waste of yarn.

Another object of the invention is to provide means for regulating the operation of the bunch builder arm of the device, whereby the size and construction of the bunch may be regulated to meet various requirements.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

Referring to the drawings:

Figure 1 is an elevational view of the bunch builder arm of the bunch building mechanism, illustrating the cams in their initial positions.

Figure 2 is a plan view thereof.

Figure 3 is a side elevational view of the builder arm, taken from the opposite side of the builder arm.

Figure 4 is a sectional view taken on line 4—4 of Figure 1.

Figure 5 is a detail view illustrating the position of the fingered cam, when the builder arm is operating under the action of the main cam of the mechanism.

Referring to the drawings in detail, the reference character 5 designates the builder arm of the bunch builder, forming the subject matter of this invention, and as shown, this arm 5 is pivotally mounted on the base of the spinning frame at 6, thereby providing what may be termed a long arm and a short arm.

Extending from the short arm of the builder arm 5, is an extension arm 7 which may be adjusted vertically by means of the set screw 8, there being provided a counterbalancing weight 9, mounted on the extension arm 7.

Connected with the builder arm 5, near the extremity of the long arm thereof, is the builder chain indicated by the reference character 10, which builder chain connects with the usual actuating arm of the ring rail, not shown, and transmits movement to the ring rail, feeding the yarn to the quill, during the filling of the quill. It will, of course, be understood that the ring rail is of the usual and well known construction, and operates to guide and regulate the yarn as it is being fed into the quill, thereby insuring against the filling becoming tangled and irregularly formed on the quill.

Supported by the builder arm 5, is a mutilated cam 11 formed with cam fingers 12 extending from the periphery thereof, a portion of the cam 11 being cut away, as clearly shown by Figure 5 of the drawings, for purposes to be hereinafter more fully described.

Arcuate-shaped openings 13 are formed in the cam 11, which accommodate the bolt 14, the bolt extending inwardly to a point where it will engage the rib or flange 15 formed on the bar 22 of the machine, whereby rotary movement of the cam 11 will be restricted.

Pivotedly mounted on one of the fingers of the cam 11, is a curved arm 16 that carries a roller 17 at its outer end. One end of the arm 16 is formed with an extension 18 adapted to engage the stop 19, restricting movement of the curved arm 16 in one direction.

This cam 11 is mounted on the bolt or shaft 20 that extends through the elongated opening 21 of the bar 22, which forms a part of the bracket 23 that is bolted to the frame of the machine, by means of the bolt 24. Thus it will be seen that due to this construction, the cam 11 may be raised and lowered, to properly adjust the cam, and that cam 26 does not operate the builder arm 5, while the builder arm is being operated by the cam 11.

Mounted on the shaft 20 is a coiled spring 25 that has one end thereof anchored at the outer end of the shaft, while the inner end is secured to the cam 11, so that after the cam 11 has rotated a predetermined distance, the spring 25 will be placed under tension, and when the cam has been released in a manner to be hereinafter more fully described, the spring will act to rotate the cam, returning the cam to its initial position.

The reference character 26 designates the main cam of the mechanism, and operates against the roller 27, that in turn is mounted within the frame 28 that is bolted to the builder arm 5.

Cooperating with the fingers 12 of the cam 11,

is a rotary cam 29, the surface of the cam between certain of the adjacent extensions or fingers 30 thereof being formed with depressions 31, so that the outer ends of the fingers 12, moving against these surfaces will bridge the recess to the end that the cam 11 and bar 5 will be moved a shorter distance than when the fingers 12 contact with the surfaces between the remaining adjacent fingers 30. When the cam 29 is moving over the roller 17, the main cam is held out of contact with the roller 27 and is not at this period of the refilling operation, operated by the main cam 26.

It might be further stated that the cam 27 is so shaped as to cause the yarn to be wound slightly higher at the top of each third stroke, than on the two preceding strokes, due to the irregular formation of the edge of the cam.

This action causes the yarn to cross more rapidly at the nose of the bottom on each third stroke and to form a tightly wound, slightly protruding nose which does not slough off in the loom.

The operation of the device is as follows:

On filling a quill, the cam 29, operating over the fingers 12 of the cam 11, causes a movement to be imparted to the builder arm, which in turn operates the chain 18, transferring a slight movement to the ring rail, not shown, causing the yarn to be formed into a bunch at one end of the quill.

When the cam 11 has made one complete revolution, the cam 29 engages the pivoted member 16, and swings the pivoted member 16 to the position shown by Figure 5, whereupon continued rotary movement of the cam 29 merely operates to rotate the roller 17, allowing the builder cam to operate a full stroke in the filling of the quill.

The main cam 26 now operates to move the builder arm a greater distance, whereby the quill is properly filled.

When the quill has been filled, the doffer operates a mechanism not shown, causing the builder arm to move downwardly, whereupon the fingered cam returns to its normal position, at the action of the spring 25.

Having thus described the invention, what is claimed is:

1. A bunch forming and quill filling mechanism, comprising a pivoted builder arm, a rotary cam mounted on the builder arm, a plurality of spaced fingers on the rotary cam, there being provided a wide space between certain of the fingers, a member pivotally mounted on one of the fingers and adapted to normally lie within the space, a main cam operating to operate the builder arm, a cam operating with the main cam and cooperating with the fingered cam whereby the builder arm is actuated to form the bunch, and said last mentioned cam adapted to move over the pivoted member whereby the main cam operates the builder arm its full stroke thus filling the quill.

2. The combination with a spinning machine and the bunch builder arm and quill filling mechanism thereof, of a bunch forming device com-

prising a rotary fingered cam mounted on the builder arm, a cam engaging the fingered cam and adapted to rotate the fingered cam whereby the builder arm is operated to build the bunch of the quill, means including a pivoted member on the fingered cam for engaging the second mentioned cam for temporarily disengaging the fingered cam and second mentioned cam, a cam operating the builder arm independently of the fingered cam, and means for returning the fingered cam to its initial position.

3. A bunch forming and quill filling mechanism, comprising a pivoted bunch building arm, a roller supported by the arm, a main cam operating over the roller and adapted to impart a vertical movement to the bunch builder arm, a small cam rotatable with the main shaft, a fingered cam operating over the small cam and adapted to impart vertical movement to the builder arm, a pivoted member carried by the fingered cam and adapted to swing outwardly beyond the fingers thereof and engaging the small cam whereby the builder arm is forced downwardly operating a full stroke, and the fingers of the fingered cam moved out of engagement with the small cam.

4. A bunch forming and quill filling mechanism comprising a pivoted bunch building arm, a ring rail actuating chain connected to the arm and actuated by the bunch builder arm, a main cam adapted to impart vertical movement to the bunch building arm, a substantially small cam associated with the main cam, a fingered cam on the builder arm and adapted to be engaged by the small cam imparting vertical movement to the builder arm, a pivoted member on the fingered cam and engaged by the substantially small cam for moving the builder arm out of operative relation with the main cam, means for returning the fingered cam to its normal position, means for adjusting the fingered cam whereby the initial position of the fingered cam is varied, and said small cam adapted to move over the pivoted member whereby the main cam operates the builder arm its full stroke filling the quill.

5. A bunch forming and quill filling mechanism, comprising a pivoted bunch builder arm, a ring rail actuating chain connected to the arm and actuated by the bunch builder arm, a main cam adapted to move the arm downwardly, a cam supported adjacent to the main cam and rotatable therewith, a mutilated fingered cam mounted on the bunch builder arm, the fingers of the last mentioned cam engaging the second mentioned cam operating the bunch builder arm, a pivoted member mounted on the fingered cam adjacent to the mutilated portion of the cam and adapted to be engaged by the second mentioned cam whereby a long stroke is transmitted to the bunch builder arm, and means for releasing the arm to the action of the main cam whereby the arm is operated to fill the quill.

JESSE LEE LYLE.
